UNITED STATES PATENT OFFICE.

CHARLES HOUSEMAN, OF ROCHESTER, NEW YORK, ASSIGNOR, BY DIRECT AND MESNE ASSIGNMENTS, TO UNDERWOOD TYPEWRITER CO., OF NEW YORK, N. Y., A CORPORATION OF NEW YORK.

PRINTING-MACHINE.

1,270,827.

Specification of Letters Patent.

Patented July 2, 1918.

Application filed October 10, 1917. Serial No. 195,841.

To all whom it may concern:

Be it known that I, CHARLES HOUSEMAN, a citizen of the Republic of France, and resident of Rochester, in the county of Monroe 5 and State of New York, have invented certain new and useful Improvements in Printing-Machines, of which the following is a specification.

The present invention relates to printing machines, and more particularly to the type in which means is provided for rupturing or breaking the paper in such a way that the changing of the matter printed is rendered difficult, an object of this invention being to 10 provide a rupturing means separate from the printing surfaces and operating to one side of the printing point to break or rupture the paper on either or both sides of the printing point so that the rupturing portions will be coincident with matter previously or subsequently printed, thus causing the printing ink to penetrate the ruptured portions and the rubbing of the paper with an eraser to tear the paper. Another 15 object of the invention is to produce a printing machine which is not limited to any certain words or expressions but is capable of producing any written instrument or document, protected to render difficult the 20 changing of the instrument or document. Still another object of the invention is to provide, in an ordinary typewriting machine, a rupturing means which will rupture or break the paper on either or both sides of 25 the printing point. A further object of the invention is to combine with a printing machine having an inking ribbon, a rupturing means which will rupture the paper or work without injury to the inking ribbon. A still 30 further object of the invention is to provide a rupturing means combined with a platen and printing mechanism and controlled by the latter.

To these and other ends the invention consists of certain parts and combinations of parts, all of which will be hereinafter described, the novel features being pointed out in the appended claims.

In the drawings:—

Figure 1 is a front view of a typewriting machine embodying the present invention;

Fig. 2 is a detail view of the line guide of the machine illustrated in Fig. 1, showing one embodiment of the rupturing means associated with said guide;

Fig. 3 is a detail perspective view of the rupturing means shown in Fig. 2;

Fig. 4 is an enlarged section through the rupturing means on the line 4—4, Fig. 2;

Fig. 5 is an enlarged detail view, partly in section, showing the position of the rupturing device with reference to the line guide;

Fig. 6 is a view similar to Fig. 5, showing the coöperation between the type bar and the rupturing device;

Fig. 7 is a horizontal sectional view in detail, showing the coöperation between the typehead and the rupturing device;

Fig. 8 is an enlarged view, showing the manner in which the paper is ruptured or broken with reference to certain letters; and

Fig. 9 is an enlarged detail view of another embodiment in which the rupturing means ruptures the paper on both sides of the printing point.

The invention is herein illustrated as embodied in a printing machine of the type known as a typewriting machine, in which the type are selectively moved to the printing point and a roller platen is employed for supporting the work and receiving the impact of the type, the platen being fed step-by-step in the direction of the printing line for producing the letter spacing and being rotatable about its longitudinal axis to produce line spacing, a suitable inking ribbon being employed and mounted in front of the platen so that the type will strike the ribbon and produce an impression on the work arranged between the ribbon and the platen. Typewriting machines of this type are so well known that further description and illustration of their mechanisms is unnecessary, the specific machine herein illustrated being known to the trade as the "Corona." It is apparent, however, that the invention is not limited to the use with a typebar typewriting machine, but may be employed in connection with any printing machine in which a platen or its equivalent is engaged by a printing mechanism of any construction.

Referring now to the drawings of the illustrated embodiment of the invention, 1, 105 indicates a roller platen having a rubber or yielding surface, 2 a type bar of the printing mechanism which is controlled by the keys 3 of a keyboard. The inking mechanism has an inking ribbon 4 which is 110

mounted on spools 5 in front of the platen 1 to be engaged by the type 6 on the type head 7. The platen, as before stated, has a rotary movement for line spacing and a 5 step-by-step movement in the direction of its length for letter spacing, as is common in machines of this type. A line guide 8 is arranged in front of the platen and the ribbon 4 lies in front of the guide, the guide 10 being provided with an opening 9 through which the type bars strike.

The rupturing means is, in this instance, in the form of a plate 10 with an opening 11 therein, through which the type 6 are 15 adapted to pass. In the embodiment shown in Figs. 1 to 8, projections 12 are extended from one side of the opening and have their free ends formed into knife edges 13, while in the embodiment shown in Fig. 9 two series of projections 12^a are provided, one on each side of the opening 11, and each projection having a knife edge 13 at its rear end. The plate 10 has a resilient portion 14 connected with an attaching portion 15, the attaching portion being secured to the line guide 8 at one side of the opening 9, so that the opening 10 of the rupturing device with the rupturing projections 12 lie over the opening 9 in the line guide. In this instance, the line guide has two headed projections 16 and the attaching portion 15 has two slots 17 and 18, the latter being curved and opening at the under side of the attaching portion, while the slot 17 is straight 25 and opens at the end of the attaching portion. This arrangement permits the rupturing device to be swung from the position shown in Fig. 2 over the opening 9 of the line guide until it occupies the position 30 shown in dotted lines in Fig. 2, in which position it may be removed from the machine. This mounting of the rupturing means permits the latter to be thrown into use at will, or to be moved to an inoperative position when not desired.

In the operation of the invention, when it is desired to rupture the paper, the rupturing means is thrown to the position shown in the full line in Fig. 2, and the 50 typewriter is operated in the usual manner. When the type head is moved upwardly, the plate 10 is engaged above and below the opening 11 by the type head 7, as shown in Fig. 6. This moves the projections 12 toward the platen and causes said projections to penetrate the paper at one side of the printing point, according to the embodiment shown in Figs. 1 to 7, or on both sides according to the embodiment shown in Fig. 9. 55 When the type head 7 strikes the plate 10, the latter yields at the point 14 so that, when the type head moves away from the device, the latter will assume its original position and the movement of the platen is not interfered with. When only one set of ruptur-

ing projections is employed, as shown in Figs. 1 to 7, the paper will be cut in horizontal lines, as shown in Fig. 8, the length of these cuts, of course, depending upon the length of the cutting edges of the projections. At the same time the cuts are made a letter is printed, for example, when the letter H of Fig. 8 is printed, the slits 19 on the letter T will be formed, while the slits on the letter H will be formed when the letter I is struck. It is apparent that as one letter is struck almost immediately after the one preceding it, the ink on the preceding letter will not be dry, so that as the paper is cut the ink will be forced into the 75 rupture. In the embodiment shown in Fig. 9, as each letter is struck a ruptured portion is provided on opposite sides thereof, so that with the printing of any one letter not only is the paper ruptured at the preceding letter, but it also is ruptured at a point where a letter is to be subsequently imprinted. In this way most of the letters will be imprinted upon a surface which has previously been ruptured and after being 80 imprinted the paper on which said letter is imprinted will be again ruptured, thus insuring the breaking up of the paper.

From the foregoing it will be seen that there has been provided a rupturing means combined with a printing mechanism in such a manner that any written instrument or document can be protected against surreptitious changing. The rupturing of the paper occurs simultaneously with the printing action in an area to one or both sides of the printing area or point. The rupturing means is operated by the printing mechanism and is arranged between the ribbon of the inking mechanism and the platen so that the ribbon is not affected by the rupturing means. In the illustrated embodiment, the invention is carried out by attaching a rupturing device to an ordinary type bar typewriting machine so that the latter may be 105 used with or without the rupturing device.

What I claim as my invention and desire to secure by Letters Patent is:—

1. In a printing machine, the combination with a printing mechanism and a platen, one of which is movable in the direction of the printing line and one of which is movable toward and from the other to produce the printing, of a paper rupturing device for rupturing the paper to one side of the printing area on each relative movement of the platen and the printing mechanism.

2. The combination with a type bar typewriting machine having a platen movable in the direction of the printing line and also having an inking ribbon struck by the type, of a paper rupturing device arranged to be struck by the type and positioned between the ribbon and the platen.

3. In combination with a typewriting ma-

- chine, having a type bar printing mechanism and a platen, a paper rupturing device engaged by the printing mechanism on each operation thereof to rupture the paper to one side of the printing point. 5
4. In combination with a typewriting machine having a platen, a type bar printing mechanism, and a ribbon inking mechanism; a paper rupturing device arranged to operate between the ribbon of the inking mechanism and the platen. 10
5. In combination in a printing machine, a platen, a printing mechanism to coöperate with the platen, an inking mechanism having a ribbon to operate between the platen and the printing mechanism, and a paper rupturing device arranged to operate between the ribbon and the platen. 15
6. In combination with a platen, a type bar printing mechanism, and a paper rupturing device mounted independently of the type bars and normally out of engagement with the work on the platen but movable by the type bars of said printing mechanism to engage the work to rupture the same. 20
7. In combination with a platen, and a printing mechanism, a paper rupturing device mounted independently of said printing mechanism for engagement with work on the platen, said device being operated by the printing mechanism to one side of the printing point. 25
8. In combination with a platen and a printing mechanism, a paper rupturing device resiliently held away from work on the platen and moved into engagement with the work by the printing mechanism. 30
9. In combination with a platen and a printing mechanism; a paper rupturing device mounted to operate between them. 40
10. In combination with a platen and a printing mechanism; a paper rupturing device mounted to operate between them and shiftable at will to and from operative position. 45
11. In combination with a platen and a type bar printing mechanism, a paper rupturing device resiliently supported in the path of the type bars and having an opening through which the type may be projected to engage the platen. 50
12. In combination with a roller platen and a type bar printing mechanism, a plate having a portion provided with an opening and normally situated in the path of the type bars, for the passage of the type through the opening, said plate having rupturing projections thereon to one side of the opening, and said plate also having a resilient portion permitting said rupturing projections to penetrate work on the platen. 55
13. In combination with a roller platen and a type bar printing mechanism, a plate having a portion provided with an opening and normally situated in the path of the type bars, for the passage of the type through the opening, said plate having rupturing projections thereon to one side of the opening, and said plate also having a resilient portion permitting said rupturing projections to penetrate work on the platen, the plate also being movably mounted to swing to and from the path of the type bars. 60

CHARLES HOUSEMAN.
